UNITED STATES PATENT OFFICE.

MARSHMAN W. HAZEN, OF NEW YORK, N. Y., ASSIGNOR TO CORONA TYPEWRITER COMPANY, INCORPORATED, A CORPORATION OF NEW YORK.

TYPE-WRITING MACHINE.

1,121,094.

Specification of Letters Patent. Patented Dec. 15, 1914.

Application filed June 23, 1908. Serial No. 439,967.

To all whom it may concern:

Be it known that I, MARSHMAN W. HAZEN, a citizen of the United States, and a resident of New York, county and State of New York, have invented certain new and useful Improvements in Type-Writing Machines, of which the following is a full, clear, and exact description.

This invention relates more particularly to carriages of front-strike or visible type-writing machines in which the carriage is adapted to be folded or moved forward when not in use to make the machine more compact.

15 One of the principal objects of the invention is to provide a typewriting machine in which the carriage together with practically all of the operating mechanism including the ribbon mechanism, escapement 20 mechanism, propelling mechanism and bell, as well as the line-spacing mechanism, may be mounted upon a support and moved with the carriage into compact relation to another part of the machine when not in use 25 and to overhang the key-levers or type-bars in order that the machine may occupy much less space when compact than when in use, to adapt the machine to be readily transported or made into a package suitable 30 for such purpose.

Another object of the invention is to provide simple and efficient mechanism for typewriting machines which while foldable with the carriage into compact relation to 35 another part of the machine, has the ribbon and the escapement mechanisms adapted to be operated by the key-levers when in a normal or working position only, and which when moved to a compact position is 40 out of operative relation with the key-levers.

A further object of the invention is to provide a machine which is light, durable and effective in use, and in which the carriage and support may be moved vertically 45 to adapt the type-heads or blocks to have a plurality of characters thereon.

With these and other objects in view, the invention will be hereinafter more particularly described with reference to the accompanying drawings, which form a part of this specification, and will then be pointed out in the claims at the end of the description.

55 In the drawings, Figure 1 is a longitudi-

nal section, partly in elevation, of one form of machine embodying my invention. Fig. 2 is a fragmentary vertical section, partly in elevation, showing the platen shift or elevating and locking mechanism. Fig. 3 is a view similar to Fig. 2 except that the parts are shown in a different position. Fig. 4 is a fragmentary sectional plan view taken on a line IV—IV of Fig. 3. Fig. 5 is an inverted plan view of the platen, carriage bed, and mechanism arranged thereon with the protecting plate on the bed removed. Fig. 6 is an enlarged fragmentary vertical and longitudinal section, partly in elevation, of a part of the escapement mechanism; and Fig. 7 is a fragmentary front elevation showing the variable friction bearing for the carriage.

While I show the invention as more particularly adapted to be applied to the form 75 of typewriter disclosed in the patent granted to Frank S. Rose, No. 754,242, dated March 8th, 1904, in which the carriage and platen has a vertical shift, and is adapted to fold over and above the finger keys, and 80 in which the type-bars have a front strike for visible writing, it will be understood that many features of the invention are equally adapted for use in connection with other forms of typewriting machines, and 85 that the invention is not limited to the particular construction and arrangement of the parts as herein shown.

The frame 10 on which the several parts are mounted may be of any suitable construction and may consist of side plates or members 11, a rear plate or member 12 integral with the side plates and with an intermediate transverse bar or plate 13 serving to brace the side members 11 substantially centrally thereof, all of which may be of aluminum for the purpose of making the same light, or of sheet metal or other material. Extending transversely of the frame at the front thereof is a bar 14 which 90 may be covered by a strip of felt 15 or other sound-deadening material and which serves to limit the downward movement of the key-levers 16, and on the outer end of the levers 16 are the finger-pieces or keys 105 17, having the usual characters as in the ordinary form of machine and which form a part of a universal keyboard. The key-levers 16 are arranged in groups or banks and are pivotally held upon a plurality of 110

bars or rods 18 which are held in parallel relation transversely of the machine. A link 20 is held to the inner end of each key-lever 16, as at 19, and said link is connected 5 to a type-bar or carrier 21 which is pivoted at 22 to a bracket 23 arranged on the rear plate 12 of the machine frame. At the forward end of each type-bar 21 is a type-block or type-head 24 having a plurality of 10 characters 25, 26 and 27 thereon, one to indicate the lower case characters, the intermediate the upper case, and the outer or 27 indicating the figures, the type-bars and brackets 23 being circularly arranged 15 to form an arc. Each key-lever when depressed is forced against the tension of a spring 28 which is fastened at one end to the key-lever, and the other end to a rod 29 so that as each key is depressed it will force 20 the type-bar upward into printing position, and as soon as released will return to its normal position, the said type-bars normally resting upon a felt strip 30 arranged upon a curved bar or plate 31 extending trans- 25 versely of the machine and supported on the bar or plate 13.

The platen 32 for holding the work may be of the usual form, and is mounted to rotate between side brackets 33 of the platen 30 frame forming a part of a movable carriage 34. The carriage is provided with a rail 35 which is adapted to move in a slot 36 in the upper surface of a bar 37 forming a part of the carriage bed 38, and at 35 the rear of said bed, while the front of the carriage is provided with a rail or guide 39 which is adapted to rest at its lower edge on a plurality of buttons or engaging devices 40 arranged along the upper face or 40 surface of the carriage bed in such a way as to reduce the friction of the carriage, and at the same time hold the carriage in its proper relation to other parts of the machine. The carriage is normally forced in 45 one direction by means of a spring carried by a drum 42, located under the carriage bed and to which a flexible connection, as a cord 42^a, is connected at one end, and at its other end to a pendent arm 43 which is 50 adjustably held by a screw 44 to a transversely extending bar 45. When the carriage is released, as will be presently described, by the movement of one of the keys while printing, the spring drum will force 55 the carriage along the bed 38 as is usual in typewriting machines. It will be seen that the spring will have a greater force for pulling the carriage in starting a line because it is wound up than it has when near 60 the end of the line, and to compensate for this variation in the tension of the spring, instead of providing simply a plurality of buttons 40, Fig. 7, to extend throughout the entire carriage bed 38 at intervals, there 65 may be arranged at one end of the machine

one or more rolls 46 which will engage the rail or guide 39 at one end thereof when the same has been moved a certain distance by the connection 42^a, the spring thus causing the carriage to move more readily at one 70 end than at the other and thereby compensating for the uneven pull thereon by the spring. The arm 43 is supported by a block 47 which is adjustable along the rod or bar 45, Fig. 1, at one end of the machine, and at or near 75 the other end of the machine and adjustably held by means of a screw 48 or otherwise is a block 49 from which, as well as the block 47, projects a guide or work-retaining finger 50 which is adjustable along the platen to 80 adapt different sizes of work to be held thereon as usual. Between the adjustable fingers 50 may be arranged a guide-plate or work table 51 which may be supported by the bar 45, and is adapted to extend 85 under and toward the front of the platen so as to guide the work, and journaled between the lug 52 on the guide-plate 51 is a friction roll 53 for causing the work sheet to be moved as the platen is rotated. 90

As an escapement mechanism and means for operating the same, the carriage 34 is provided with a rack-bar 55 under the same, and this rack-bar is provided with the usual ratchet-shaped teeth which are adapted to 95 be engaged by the escapement pawls or dogs 56 and 57, Figs. 1 and 6, one of which, as 56, is fixed and the other, as 57, is movable, and said dogs are adapted to permit the carriage to move the distance of a single tooth as 100 usual when the dogs are moved laterally transversely of said rack-bar. The dogs 56 and 57 are carried by an arm 58 which is pivoted at 59 to the carriage bed and has its opposite end, as 60, guided in a slot 61 of a 105 bracket 62 so as to permit the dogs to be moved laterally of said rack-bar allowing the carriage to escape one tooth at a time and causing the dogs to be swung in an arc of a circle across the face of the rack in the 110 same plane as the rack, instead of a direct line, thus making the dogs engage the rack teeth at one point instead of along the entire surface, thereby materially reducing the wear and friction thereof. A spring as 63 115 is arranged on the carriage bed, Fig. 6, and has one end passing through the fixed dog 56 and is so arranged that it will only force the dog and the arm in one direction, and arranged on the arm 58 is a stop 64 which 120 is adapted to engage a projecting part 55 of the movable dog 57, in order to limit its movement, the said dog being normally held against movement in one direction by the spring 66, and in the opposite direction by 125 a spring 67, though instead of the two springs a single spring may be employed if desired. To operate the escapement no matter what position the carriage may be in, a movable bar 68 of an escapement or rocking 130

frame is arranged transversely of the machine, and said bar is provided with a collar tappet or projecting part which is adapted to engage the head 60 of the arm 58 to move 5 the escapement dogs against the action of the spring 63. This bar is held in the upper end of the levers or arms 70 of the rocking frame. The arms 70 are pivoted on opposite sides of the machine to a trans- 10 versely-extending rod or bar 71, and in the upper end of each of said arms 70 is a vertically arranged slot 72. A bell-crank or angular lever 73 is pivoted at 74 to a part of the machine frame on each side thereof, 15 and has one end, as by a screw 75, guided in the slot 72 of its coöperating arm 70 and its other end connected by a link or rod 76 to a universal bar 77. This universal bar 77 extends transversely of the machine over each 20 key-lever so that as each key is depressed, it will raise the bar 77 and move the bell-crank levers 73 on their pivot 74 and force the bar 68 outward and thereby move the escapement arm 58 carrying the dogs against the 25 tension of the spring 63.

The arms or levers 70, Fig. 1, may be forced inward by the springs 77^a which are held at one end to the part 12 of the frame and engage the levers 70 at their free ends. 30 An adjusting screw 77^b is adapted to engage each spring 77^a and serves to vary the pressure of the springs against the levers 70, and by means of the bell-crank levers 73 and links 76, the universal bar 77 will be forced 35 against the action of the key-levers with any desired pressure. This action of the springs 77^a not only serves to permit the force required to operate the type-bars to be changed, but they serve to restore the type- 40 bars and key-levers to their normal position. If desired the springs 28 for each key-lever may be dispensed with.

The machine is provided with means for raising the entire carriage bed and mechanisms carried thereby to different heights, 45 to position the platen 32 properly with respect to the upper case characters and the figures on the type-heads or blocks so that the same will properly strike the work held 50 by the platen, and means are also provided whereby the platen and the mechanism movable therewith may be locked in its different positions. The cap-shifting lever 78 has its inner end fixed to a transverse rod 79, which 55 is pivoted to the machine frame. The lever 78 is extended inward and engages the rod 80 so that the two rods 79 and 80 may be moved in unison, and projecting from the rod 79 is an arm 81 in which one end of the 60 rod 80 is fixed. This arm 81 has a pivotal connection with the rod 71 at its inner end, and said rod at its ends engages vertically movable slides 82 each of which is movable in a bearing 83 located at the upper end of 65 a bracket which is held to the rear part of

the machine frame, so that as the lever 78 is depressed the arm 81 will raise the slides and lift the carriage bed, platen and mechanism carried thereby. At the opposite side of the machine frame is arranged the figure-shift lever 85 which is pivoted to one of the transverse bars or rods 18, and has its inner end connected by a link 86 to the rod 80 and through the latter to a lever 87, the said link being provided with a slot 88 which spans the rod 80 so as to permit a relative independent movement of the rod and the link. The rod 80 is held in the lever 87, and said lever has its outer end pivoted to the transverse rod 71 which operates the slides 82 connected therewith as already described in connection with the cap-shift lever and which causes the platen, carriage and mechanism to be elevated, but to a different degree to that obtained by depressing the shift lever 78. A bracket or part 89 extends outwardly from the top of one of the slides 82 and said bracket may be fastened to the inner surface of an arm 90, and at the opposite end of the frame is a similar arm 91. 90 These arms 90 and 91 project outwardly and are pivotally held to bars 92 forming a part of the foldable support, the said bars 92 being held at one end to the carriage bed whereby the platen and mechanism carried thereby may be folded over as shown in dotted lines in Fig. 1.

A lever or arm 93 is pivoted at 94 to one of the sides of the frame, Figs. 2 to 4, and this lever is normally forced in one direction or toward the keys by means of a spring 95, the upper end of which engages one of the brackets 84. The upper end of the lever 93 is provided with a head 96, and this head may be provided with two screws 97 and 98 or other means which are adapted to engage an inturned end 99 of the bracket or plate 89 to limit the upward movement of the carriage bed, platen and mechanism movable therewith according to the position of said arm 93. This arm or lever 93 is provided with a projection 100 which has its outer edge beveled, and is adapted to be engaged by the inner beveled end of the figure-shift lever 85 so that when said latter lever is depressed the inner edge thereof will engage the cam projection 100 and force the lever 93 inward to place the screws 98 in alignment with the inturned end 99 of the plate or bracket 89. At the same time that the figure-shift lever is depressed, the slides 82 will be elevated through the link 86, and arm 87 so as to lift the carriage, platen and mechanism movable therewith until the inturned end 99 engages the screw 98 or other device 110 thereby limiting the upward movement of the part referred to, and as soon as said lever is released, the parts will return to their normal position. The screw 98 is employed 115 to permit nice adjustment, and the screw 97 120

125 thereby limiting the upward movement of the part referred to, and as soon as said lever is released, the parts will return to their normal position. The screw 98 is employed 130 to permit nice adjustment, and the screw 97

is arranged to normally engage the inturned end 99 of the plate 89. This screw 97 works in connection with the cap-shift lever, and when the latter operates the transverse rod 71 and the slides 82 to elevate the same and the means supported thereby, the inturned end of the bracket 89 engages the lower end of the screw 97 thus limiting the upward movement of said slides. The screw 97 is moved inward out of the path of movement of the inturned end 99 when the figure-shift lever is depressed and places the screw 98 in position to engage the end 99, thus giving the carriage and platen three positions, the normal one being when the arms 91 are resting on the machine frame and for the lower case characters, an intermediate position when the cap-shift lever is operated for the upper-case, and a third position when the figure-shift lever 85 is operated, thus properly positioning the platen and the several mechanisms to have the type properly strike the work while printing.

The carriage, platen and several parts supported by the slides 82 may be locked in either of the elevated positions in which the same is moved by either the cap-shift levers or the figure-shift lever. To effect this a lock-lever 101 may be employed. This lever is pivoted at 102 adjacent to the inner end of the cap-shift lever 85, and has its lower end, as 102^a, bent in the form of a hook and provided with two recessed parts 103 and 104 which are adapted to engage the transverse rod 80 or a projection on the arm 87 which is moved by both of the shift levers. As will be seen when the cap-shift lever is operated, it will raise the transverse rod 80 a certain distance, and by forcing the lock-lever 101 downward to the position shown in full lines in Fig. 3 the slides 82 or elements will be locked in their intermediate position. This platen shift mechanism is the same as that disclosed in my divisional application Sr. No. 499,876, filed June 3, 1909.

The machine is provided with the usual spacing means 105 which has two spacing-lever members 106 joined by a space-bar 107, and said means is pivoted to one of the transverse rods 18, and has its inner end forked, as at 108, Fig. 1, to engage the universal bar 81 for moving the escapement in substantially the same manner as the key-levers 16, and such spacing device, as well as the keys, operate the escapement no matter what position the platen and parts supported by the slides 82 may be in, as the bar 68 is arranged to move with the slides and the carriage.

As a line-spacing mechanism, a lever 113 is pivotally held to the platen shaft in a manner similar to that disclosed in my divisional application, Sr. No. 499,874, filed June 3, 1909. A pawl is pivoted to the lever 113 and is adapted to engage the teeth of a

ratchet wheel on the platen shaft as in said application, the whole mechanism being adapted to shift with the carriage in its vertical and folding movements.

The ribbon may be shifted with respect to the type to adapt the same to have more than one color, and supported on the carriage bed, so as to be elevated therewith, are the ribbon spools 142 and 143. These spools are each held to rotate with or independently of a sleeve through which passes a shaft or spindle, both of which are fixed to the arms 92, the latter being pivotally held to the arms 91. Each sleeve is threaded at its upper end and said end is engaged by a thumb-nut 147 which is adapted to hold the spool against rotation, or to permit the spool to rotate to wind the ribbon from one spool to the other according to which nut 147 is tightened or released. The ribbon 151 may be fastened to a sleeve part of the spools, and said spools are supported by brackets 153 which are secured to the bars 92, and are each provided with a ribbon guide 154. This guide 154 is in the form of a loop having a slot at one side, as at 155, through which the ribbon may be passed, and said loop may be arranged in a substantially vertical plane. Each spool sleeve is provided with a gear 156 which is engaged by a worm, and on the spindle or shaft 159 of each worm is a ratchet wheel 160 which is engaged by a pawl 161 carried by the upper end of each lever 70, so that when said lever is moved the pawl will be made to impart a step-by-step movement to the worm and the ribbon whenever any of the keys are depressed, the said ratchet wheels each being engaged by a spring-pressed pawl or detent 162 to prevent the ratchet wheel from moving except in one direction. As will be seen, the gears 156 are both moved when the ratchet wheels 160 are operated through the depression of the keys but on the return movement of the levers 70, and only that spool is operated in which the nut 147 has been tightened, the ribbon thereby being made to move in either direction according to which spool is loose.

The ribbon 151 passes inwardly to the front part of the platen as shown best in Fig. 5, and is passed through the loop or slotted portion formed in the end of a vibratory arm 164. This arm 164 is pivoted to the inner edge of the carriage bed, and has a tooth or stop portion 166 which is engaged by one end of a bell-crank or angular lever 167, and said arm is normally forced in one direction against the action of the lever 167 by means of a spring 168 which is attached to the lever at one end and to the carriage bed at the other. The lever 167 is pivoted at 169, and has its arm 170 adapted to strike a stop or projection 172 and its outer end arranged in the path of a device carried by

the bar 68 of the escapement or rocking frame. The ribbon mechanism is shiftable and foldable with the carriage and bed and is adapted to be operated by the key-levers when in its normal working position only, as fully set forth in my divisional application, Sr. No. 499,875, filed June 3, 1909.

The carriage may be provided with the usual or any preferred means for ringing the bell or alarm when the carriage is moved approximately the length of a line. As shown, a bell 184 is provided which is adapted to be engaged by a hammer 185 carried by an arm 186, the said hammer being normally held in one position by a spring 188, and carried by the hammer arm 186 is an arm or member 189 which is pivoted to the arm 186 and is forced in one direction by a spring 190 against a stop 191. When the arm 43, which is connected to the drum carrying the spring for moving the carriage, engages the arm 189 and passes the same, the spring 188 will cause the hammer to strike the bell.

A large part of the mechanism herein shown and described is claimed only broadly as such features including the platen shift, feed mechanism, ribbon mechanism, line-spacing mechanism, and other features are set forth and claimed in other applications which are divisions of this case.

From the foregoing, it will be seen that simple and efficient means is provided whereby a carriage and platen may be moved with the ribbon mechanism, escapements mechanism, and other features into compact relation to another part of the machine in order to occupy less space than when in use; that simple means is provided whereby the carriage and its support may be maintained in coöperative relation to the key-levers when in normal working position; and that said machine may be made very light and is particularly adapted for transportation and other purposes.

Having thus described my invention, I claim as new and desire to secure by Letters Patent:—

1. In a visible typewriting machine, the combination of a universal keyboard having key-operated levers, type operated by said levers, a foldable support, a platen and a carriage therefor held to said support and foldable therewith out of the path of the type into close relation to the keyboard without disturbing the relation between the key-operated levers and the type, ribbon mechanism mounted upon the support to which the carriage is held, means for shifting the support in a vertical direction, together with means for letter-spacing the carriage and operating the ribbon mechanism in whatever shifted position the support may be moved.

2. In a front-strike typewriting machine,

the combination or a universal keyboard having key-operated levers, upwardly and rearward moving type-bars operated by said levers, a foldable support, a platen and a carriage therefor held to move along said support and foldable therewith out of the path of the type into overhanging relation to the keyboard without disturbing the relation between the key-operated levers and the type, ribbon mechanism mounted upon the support to which the carriage is held, means for shifting the support in a vertical direction to adapt the type-bars to carry a plurality of type, together with means for letter-spacing the carriage and operating the ribbon mechanism in whatever shifted position the support may be moved.

3. In a front-strike typewriting machine, the combination of a universal keyboard having key-operated levers, type-bars carrying a plurality of type and each bar operated by one of said levers, a carriage, a platen mounted in the carriage and normally in the path of movement of the type and movable forward with the carriage away out of the path of the type and into compact relation to the forward part of the machine when not in use without disturbing the relation between the type-bars and key-operated levers, ribbon mechanism partaking of the compact movement of the carriage, and feed mechanism coöperating with the platen and the key-operated levers when the latter are moved to operate the platen for letter spacing and when the parts are in normal working position.

4. In a front strike typewriting machine, the combination of a universal keyboard having keys, type bars operated by said keys, a carriage, a platen mounted on said carriage and normally in the path of said type bars, means for shifting the platen carriage in a vertical direction, feed mechanism coöperating with the keys to move the platen and carriage for letter spacing, ribbon mechanism located to partake of the compact movement of the carriage, and a foldable support whereby the platen and carriage and keys of the keyboard may be brought into close relation to make the machine more compact when not in use than when in a normal working position.

5. In a typewriting machine, the combination with a vertically movable support having two foldable members, of a platen and a carriage therefor held to one of said members, a ribbon and mechanism therefor for moving the ribbon in either direction mounted upon the member to which the carriage is held, means for raising the support, means for locking the same in its adjusted position, together with means for operating and shifting the carriage and ribbon-operating mechanism in whatever elevated position the support may be moved.

6. In a typewriting machine, the combination with a vertically movable support having two foldable members, of a platen and a carriage therefor held to one of said members, a ribbon and mechanism therefor for moving the ribbon in either direction mounted upon the member to which the carriage is held, means for raising the support, together with means for locking the support and mechanism supported thereby in an adjusted position.

7. In a typewriting machine, the combination with a two-part foldable support, of a platen and a carriage therefor held upon said movable support, a ribbon and mechanism therefor for moving the ribbon mounted upon the support, means for elevating the support to different positions, and means for locking the support in its different adjusted positions.

8. In a typewriting machine, the combination with key-levers, of a vertically movable support, a platen carriage mounted on said support and foldable into substantially overhanging relation to the key-levers, ribbon mechanism for moving a ribbon in either direction and mounted upon the support and foldable with the carriage, means for raising the support, means for locking the same in its raised position, together with means for operating the ribbon mechanism and moving the carriage when in their normal working position.

9. In a typewriting machine, the combination with a vertically movable support, of a platen carriage foldable forward into compact relation to another part of the machine when not in use, ribbon mechanism for moving a ribbon in either direction mounted upon the support, means for raising the support, together with means for locking the support and mechanism supported thereby in an adjusted position.

10. In a typewriting machine, the combination with a support, of a platen carriage foldable forward into compact relation to another part of the machine when not in use, ribbon mechanism for moving a ribbon and mounted upon the support, means for elevating the support to different positions, and means for locking the support in its different adjusted positions.

11. In a type-writing machine, the combination with key-levers and type-bars operated by said key-levers, of a carriage, a platen normally in the path of said type-bars and shiftable with the carriage into compact relation to another part of the machine when not in use, ribbon mechanism shiftable with the carriage, and feed mechanism co-operating with the platen and the key-levers when the latter are moved to operate the platen for letter spacing.

12. In a typewriting machine, the combination with a vertically movable support

having foldable members, of a platen and a carriage therefor held to one of said members, mechanism for moving a ribbon in either direction and mounted upon the member to which the carriage is held, means for raising the support, together with means for operating and shifting the carriage and ribbon-operating mechanism in whatever raised position the support may be moved.

13. In a typewriting machine, the combination of a movable support having foldable members, of a carriage held to one of said members and foldable therewith into overhanging relation to the front part of the machine, mechanism for moving a ribbon in either direction and mounted upon the member to which the carriage is held, means for shifting the support, together with means for operating the carriage and ribbon mechanism in whatever shifted position the support may be moved.

14. In a typewriting machine, the combination of a vertically movable and foldable support, a keyboard, a carriage held to said support and foldable therewith into overhanging relation to the keyboard, ribbon mechanism mounted upon the support and foldable therewith, means for raising the support and carriage, together with means for locking the support and mechanism supported thereby in an elevated position.

15. In a typewriting machine, the combination of a support, a carriage held to said support and movable therewith into compact relation to another part of the machine to occupy less space than when in use, ribbon mechanism mounted upon the support and partaking of its compact movement, means for raising the support and carriage, together with means for locking the support and mechanism supported thereby in an elevated position.

16. In a typewriting machine, the combination of a two-part foldable support, a platen carriage mounted upon said movable support, ribbon mechanism mounted upon the foldable part of the support, and means for shifting the carriage and ribbon mechanism to different positions.

17. In a typewriting machine, the combination of a foldable support, a keyboard, a carriage mounted upon said support and foldable with the support over the keyboard, ribbon mechanism mounted upon the support and foldable therewith, means for shifting the support to different positions, and means for locking the support in its different shifted positions.

18. In a typewriting machine, the combination of key-levers, a vertically movable support, a platen carriage mounted on said support and foldable into substantially overhanging relation to the key-levers, ribbon mechanism for moving a ribbon in either

- direction and mounted upon the support and foldable with the carriage, means for shifting the support and carriage, together with means for operating the ribbon mechanism and moving the carriage when in their normal working position.
19. In a typewriting machine, the combination of key-levers, a vertically movable support, a platen carriage mounted on said support and foldable into substantially overhanging relation to the key-levers, ribbon mechanism for moving a ribbon in either direction and mounted upon the support and foldable with the carriage, means for raising the support, together with means for operating the ribbon mechanism and moving the carriage when in their normal working position.
20. In a typewriting machine, the combination of a vertically movable support, a platen carriage foldable forward into compact relation to another part of the machine when not in use, ribbon mechanism for moving a ribbon in either direction mounted upon the support, and shift means for raising the support.
21. In a typewriting machine, the combination of a movable support, a keyboard, a platen carriage foldable forward with the support over the keyboard when not in use, ribbon mechanism for moving a ribbon in either direction mounted upon the support and foldable therewith, means for raising the support, together with means for locking the support and mechanism supported thereby in an elevated position.
22. In a typewriting machine, the combination of a support, a platen carriage movable forward into compact relation to the forward part of the frame of the machine when not in use, ribbon mechanism mounted upon the support and movable therewith, and shift means for moving the carriage to different positions.
23. In a typewriting machine, the combination of key-levers and type-bars operated by said key-levers, a carriage, a platen normally in the path of said type-bars and movable forward with the carriage into compact relation to the forward part of the machine when not in use, ribbon mechanism partaking of the compact movement of the carriage, and feed mechanism cooperating with the platen and the key-levers when the latter are moved to operate the platen for letter spacing.
24. In a typewriting machine, the combination with key-levers and a type-bars operated by said key-levers, of a carriage, a platen mounted thereon and normally in the path of said type-bars and bodily shiftable with the carriage into compact relation to another part of the machine when not in use, ribbon mechanism also shiftable with the carriage, means for moving the carriage vertically, and feed mechanism cooperating with the key-levers to move the platen for letter spacing.
25. In a typewriting machine, the combination with a support, of a carriage movable lengthwise of said support, letter-spacing mechanism, a plurality of buttons arranged at one end of the support and rolls at the other to vary the friction of the carriage in its movement along the support, and propelling mechanism for the carriage.
26. In a typewriting machine, the combination with a support, of a carriage movable lengthwise of said support, letter-spacing mechanism, spring-actuated propelling mechanism for the carriage, and means interposed between the carriage and bed and forming a bearing for the carriage and compensating for the varying tension of said propelling mechanism.

This specification signed and witnessed this 19th day of June, A. D. 1908.
